UNITED STATES PATENT OFFICE

ALMER H. BRODBECK, OF ST. LOUIS, MISSOURI, ASSIGNOR TO AMERICAN STOVE COMPANY, OF ST. LOUIS, MISSOURI, A CORPORATION OF NEW JERSEY

DESIGN FOR A COMBINED COCK HANDLE AND PLATE

Application filed August 22, 1929. Serial No. 32,501. Term of patent 14 years.

To all whom it may concern:

Be it known that I, ALMER H. BRODBECK, a citizen of the United States, residing in the city of St. Louis and State of Missouri, have invented a new, original, and ornamental design for a Combined Cock Handle and Plate, of which the following is a specification, reference being had therein to the accompanying drawings.

Figure 1 is a view in front elevation of the

combined cock handle and plate, showing my new design.

Figure 2 is a side view of the new design.

I claim:

The ornamental design for a combined cock handle and plate, as shown.

In testimony whereof, I hereunto affix my signature.

ALMER H. BRODBECK.
